COMBINED CURTAIN ROD AND BRACKET ASSEMBLY

Stuart D. Burt, Jr., Monrovia, Calif., assignor to
Drapery Hardware Company, Ltd., Monrovia,
Calif., a corporation of California

Application January 10, 1951, Serial No. 205,261

2 Claims. (Cl. 211—105.2)

1

The present invention relates to curtain rods and, more particularly, to an improved prong bracket for supporting the rods in position.

An important object consists in providing a curtain rod having its ends opened and of substantially channel or C-shape, and associating with the ends of the rod, supporting brackets for detachably receiving the rod. Each bracket is formed from a single piece of durable wire or rod and has at one end a horizontally disposed threaded shank arranged to be secured to a window or door frame. The shank portion of the rod at its forward end is bent upwardly to form a projection or prong that is connected to a depending vertical portion which terminates in an upwardly curved or looped end portion positioned below and spaced from the threaded shank end portion. The top and bottom of the channel ends of the curtain rod are provided with vertically aligned apertures, the top aperture being arranged to initially receive the prong on the bracket so as to be swung downwardly thereon as a pivot, in order to position the vertical portion and the looped portion of the bracket within the open end of the curtain rod when the parts are assembled. The aperture in the bottom channel is arranged to receive the looped end portion of the bracket to yieldably maintain the same in a fixed position and prevent the accidental removal of the rod by a direct vertical upward movement.

A further object consists in providing improved means for packing and transporting the curtain rods and brackets and in such a manner as to insure the brackets not damaging or scratching the rods, and which allows easy dispensing of the curtain rods and brackets and also avoids the necessity of separately packing the brackets.

Other objects and advantages of the invention will become apparent from the following description when taken in conjunction with the accompanying claims and drawings.

Referring to the drawings, in which is shown a preferred embodiment of the invention:

Figure 1 is a detail side view of a one-piece prong bracket constructed in accordance with the present invention.

Figure 2 is a side view with parts in section showing one end of a curtain rod or the like connected to a window or doorframe by the improved bracket.

Figure 3 is a view similar to Figure 2 showing the initial positioning of one end of the curtain rod when being mounted or hooked on the bracket, and

2

Figure 4 is a sectional horizontal view of a door or window frame showing an extensible curtain rod connected thereto by the improved bracket structure.

5 Referring to the drawings, 10 indicates the frame of a window, door or the like, 11 a curtain rod which, as shown, is of the extensible type having an inner rod portion 12 that is arranged to telescope within a tubular outer portion 13. 10 The ends 14 of the rod may be bent laterally and be disposed substantially parallel to each other, and open as at 15 (Fig. 3). The extension rod 12 is shown of substantially channel or C-shape in cross section but, manifestly, may be of any 15 suitable configuration and is provided with a top channel portion 16 and a bottom channel portion 17, which are preferably formed with vertically aligned apertures 18 and 19 that are spaced from the ends of the curtain rod a predetermined distance.

The ends 14 of the rod 12 are detachably connected to the window or doorframe 10 by spaced brackets 20 (Fig. 4). Each of the brackets 20 is formed from suitable durable wire or rod and 25 is shaped or bent to provide a substantially horizontally disposed end or shank 21 (Fig. 1) having a threaded portion 22 for connecting the bracket to a window frame, casing or the like. The outer end of the shank 21 is bent or curved 30 upwardly to provide a prong or projection 23 which has extending downwardly therefrom a vertical straight portion 24 that terminates in an inwardly and upwardly curved or looped lower end portion 25 which is positioned below and 35 spaced from the shank end 21.

In order to properly position the curtain rod on a window frame or the like, a pair of the one-piece prong brackets 20 are screwed in position at the proper points on the window frame, and 40 each end of the rod is tilted upwardly so that its aperture 18 receives the projection 23 of the bracket. The rod is then allowed to swing downwardly in the direction of the arrow 26 (Fig. 3) so that the bottom channel 17 slidably receives 45 the looped portion 25 of the bracket and the latter yieldably engages the aperture 19 in the bottom channel 17 in order that the rod 12 may be maintained in its proper horizontal or curtain carrying position, as shown in Figure 2. The 50 loop 25 of the bracket is preferably sufficiently yieldable to provide a spring action which allows the end of the curtain rod to be snapped into engagement therewith and be maintained firmly in a fixed position when the parts are assembled. 55 The looped portion 25 also constitutes a stop for limiting the screwing engagement of the shank

21 with the window frame. The apertures 18 and 19 provide means for allowing the rod to be interchangeably used as either a right or left rod and while the lower opening 19 could be omitted, its presence insures the bracket being firmly engaged in the bottom channel member when the parts are set up so that the curtain, drapery or the like carried by the extension rod will be hung properly.

As the brackets are directly connected to the window frame or the like by their threaded shanks, it will be seen the use of spaced nails for connecting the brackets is omitted. Moreover, the screwing action of the bracket into the window frame gives greater holding quality than 15 nails and requires only one hole in the frame. Further, the prong bracket may be made at a minimum expenditure of time, labor and cost, and when the curtain rod is applied, the brackets are practically invisible so as to give a pleasing and attractive appearance to the curtain rod. The 20 slideable locking engagement of the looped portion 25 with the bottom opening 19 in the end of the curtain rod provides means which urges the prong 23 into firm engagement with the wall of the aperture 18 and prevents the rod from being accidentally disengaged from its projection or hook support 23.

It will be seen that the bracket 20 is so shaped and constructed that it may be detachably connected to an end of the curtain rod so as to be packed and transported and without danger of scratching or marring the rod. In this connection, it might be mentioned that rods are now mainly packed in bulk with the face of one rod resting on the back of another and separated by a layer of paper. Moreover, the brackets and nails which are used to connect them to the window frame or casing have to be packed separately. As contrasted to this cumbersome and expensive way of handling curtain brackets, it will be seen that the brackets can be packed in the end channel portions of the rod without projecting above the channel. Moreover, the brackets are so packed in the rods as to be easily dispensed and sold over the counter. As the opened end of the solid section 11 of the channel rod 12 is of slightly smaller size than the end of the outer section 13, it will be seen that the dimensions of the bracket 20 are such relative to the end openings 15 in the rod 12, that the yieldable looped portion 25 will slidably fit within either end opening 15 with a spring or snap action. Moreover, the curtain rod may easily and conveniently be removed from the brackets upon the application of a slight upward and arcuate pressure in the direction of the arrow in Figure 1, so as to cause the release of the bottom channel member from engagement with the yieldable loop 25, to detach the curtain rod from the bracket. Thus, when the parts are assembled, the rod is maintained firmly in position and will not become loose nor can it be disengaged from the brackets upon a direct vertical pressure,

but only by an upward tilting movement about the prong 23 as a pivot.

It will be understood that the form of the invention shown is merely illustrative and that such 5 changes may be made as come within the scope of the following claims.

I claim:

1. A curtain fixture including in combination a curtain rod having open ends, each of said ends being provided with an aperture in the top thereof, supporting brackets arranged to extend into the open ends of said rod, each of said brackets including a rod member having a substantially horizontally disposed threaded shank and an upwardly extending projecting portion connected to a depending inclined portion terminating in an upwardly and inwardly curved loop portion, the projection on said bracket arranged to extend through an opening in the end of said curtain rod, and the inclined portion and loop portion of said bracket arranged to be positioned within the end of the rod when the parts are assembled, said loop portion engaging the inner wall of the end of the rod so as yieldably to maintain the same in a fixed position.

2. A curtain fixture including in combination a curtain rod having substantially channel shaped ends, each end being provided with vertically aligned apertures in the top and bottom walls thereof, supporting brackets arranged to extend into the ends of said rod, each of said brackets being formed from a one-piece wire member having a substantially horizontally disposed threaded shank provided with an upwardly extending projecting portion, said projecting portion connected to a depending inclined portion terminating in an upwardly and inwardly curved lower end forming a loop portion, the projection on said bracket arranged to extend through the aperture in the top of said curtain rod and the inclined portion and loop portion of said bracket arranged to be positioned within the end of the curtain rod when the parts are assembled, said loop portion engaging the inner wall of the curtain rod and the aperture in the bottom thereof with a snap action so as yieldably to maintain the same in a fixed position.
